ATTORNEY

UNITED STATES PATENT OFFICE.

FREDERICK M. MUNROE, OF SPRINGFIELD, MASSACHUSETTS, ASSIGNOR OF
TWO-THIRDS TO CHARLES M. SHEDD AND FRED A. NICKERSON, BOTH
OF SAME PLACE.

LACE-FASTENING.

SPECIFICATION forming part of Letters Patent No. 308,569, dated November 25, 1884.

Application filed March 29, 1884. (No model.)

To all whom it may concern:

Be it known that I, FREDERICK M. MUNROE, a citizen of the United States, residing at Springfield, in the county of Hampden and State of Massachusetts, have invented new and useful Improvements in Lacing Fastening Devices for Wearing-Apparel, of which the following is a specification.

This invention relates to improvements in devices for easily and quickly securing the ends of lacing-strings to shoes and other articles of wearing-apparel to hold the lacings in place after they have been woven across each other, in the usual manner, the object being to provide an improved device for the above-named purpose which will hold securely the end of the lacing without any knotting or tying whatever.

In the drawings forming part of this specification, Figure 1 illustrates a shoe having applied thereto a lacing-fastener constructed according to my invention. Fig. 2 is a view of the fastener and of an eyelet employed therewith. Fig. 3 is a transverse section on a line $x x$, Fig. 2.

In the drawings, a is the fastener, which is constructed from suitable metal of a springy nature, and consists of a head, n , preferably of circular form, extending from which is a flat arm, i , which is slightly tapering in thickness from said head to the end thereof. The end of arm i is bent over upon itself, as shown in Fig. 2, and near where the bend is made is formed, branching from the arm i , a post, e , between the inner face of which and the adjoining edge of the arm i is sufficient space to draw the end of the lacing D , as shown in Fig. 1. The end e of the arm i , which is bent over upon itself, as shown in Fig. 2, is bent quite near to that portion of said arm under it, leaving a space therebetween at the edge adjoining post e much narrower than the thickness of the lacing which is to be drawn into the aperture so formed. The lip e is bent to an

incline transversely to that portion of arm i thereunder, as shown in Fig. 3, so that the edge of lip e which adjoins post e is much nearer to the surface of arm i than is the opposite edge, whereby the edge of lip e next to post e is made to bite firmly upon the lacing drawn thereunder and prevent it from slipping.

The fastener a is secured to a shoe by perforating the latter, putting the rivet b through said perforation, placing head n over the rivet, and heading down the latter, in the usual way.

The fastener is secured to gloves, corsets, and other articles of wearing-apparel in substantially the same manner.

The manner of fastening the end of the lacing by means of my improved fastener is illustrated in Fig. 1—that is to say, the end of the lacing is drawn between the lip e and the arm i thereunder, and drawn between the post i and the edge of the lip, leaving it in the position shown in said last-named figure. The slight turn of the lacing given to it, as shown, by being drawn around the corner of post e , together with the aforesaid bite of the lip e , thereby secures the end of the lacing D against any possibility of slipping.

What I claim as my invention is—

The within-described improved lacing-fastener, consisting of a perforated head, substantially as described, having an arm extending therefrom, the end of which is bent over upon itself to form a spring-clip, one edge of said clip being nearer to the arm under it than the other, and having a post standing near the edge of said clip formed on the end of a branch from said arm, and extending in a direction across the opening between said clip and the arm thereunder, substantially as set forth.

FREDERICK M. MUNROE.
